OUTDOOR DRIVE BY FOOD MARKET SALES BUILDING

Richard H. Benner, 7655 Wilmington Pike, Dayton, Ohio

Filed Feb. 19, 1962, Ser. No. 68,866

Term of patent 14 years

(Cl. D13—1)

FIG-1

I claim:

The ornamental design for an outdoor drive by food market sales building, substantially as shown and described.
